UNITED STATES PATENT OFFICE.

ALEXANDER H. MILLER AND FRANK A. ENGLAND, OF PHILADELPHIA,
PENNSYLVANIA.

GROCER'S BIN.

SPECIFICATION forming part of Letters Patent No. 743,009, dated November 3, 1903.

Application filed July 31, 1903. Serial No. 167,663. (No model.)

To all whom it may concern:

Be it known that we, ALEXANDER H. MILLER and FRANK A. ENGLAND, both citizens of the United States, residing at the city of Philadelphia, in the county of Philadelphia and State of Pennsylvania, have jointly invented 5 certain new and useful Improvements in Grocers' Bins, of which the following is a specification.

10 Our invention has relation to a bin adapted for use by grocers, pharmacists, or other trades people, and in such connection it relates to the construction and arrangement of such a bin.

15 The principal object of our invention is to provide in a bin, in conjunction with the front wall thereof, a display-front arranged to fit into and interlock with the front wall of the bin, said display-front being removably secured to the front wall of the bin proper and 20 having a display-compartment entirely separated from the bin-compartment by the front wall of said bin.

25 The nature and scope of our invention will be more fully understood from the following description taken in connection with the accompanying drawings, forming part hereof, in which—

30 Figure 1 is a front elevational view of a bin and its bin chamber or casing embodying main features of our invention. Fig. 2 is a central cross-sectional view of Fig. 1. Fig. 3 is a perspective view of the front wall of the bin with the display-front removed therefrom, and Fig. 4 is a perspective view of the 35 display-front removed from the bin and illustrating its interior construction and arrangement.

40 In the drawings our invention is illustrated as applied to a tilting bin, although it will be understood that it may also be applied to a sliding or even to a fixed bin without departing from the spirit of our invention.

45 Referring to said drawings, *a* represents the bin chamber or casing, in which a bin *b* is pivotally supported, as at *b'*, to oscillate in said chamber or casing *a*, as clearly illustrated in full and dotted lines in Fig. 2. The front wall *b*² of the bin *b* is provided on its 50 front face with a beading or molding *b*³, forming a central countersunk portion *b*⁴.

While this manner of securing the central countersunk portion *b*⁴ is preferable by reason of its simplicity, yet, if desired, the front face *b*² of the bin *b* may be sufficiently thick 55 to permit of the countersunk portion *b*⁴ being cut directly therein. The lower edge *b*⁵ of this countersunk portion *b*⁴ is preferably downwardly beveled, while the remaining edges are straight. Into this countersunk 60 portion *b*⁴ of the front wall *a*² of the bin *b* is arranged to fit and interlock the rear face of a display-front *d*. This display-front *d* has its front face *d'* preferably downwardly and inwardly projecting to form a "swell" front, 65 and the upper portion of this swell front is open, and by preference this opening in the swell front is glazed, as at *d*². Back of the glass *d*² is fitted a removable false back *d*³, having at either side a bolt or suitable locking 70 means *d*⁴, engaging one of a series of slots *d*⁵ in the sides of the interior of the swell front *d*, as illustrated in Fig. 4. The space between the false back *d*³ and glazed front *d*² is utilized to receive samples of the goods to be displayed. The goods when once placed in this 75 space are hermetically sealed by the surrounding walls of the back or rear face of the display-front *d*, as well as by the front wall *b*² of the bin proper, as clearly illustrated in Fig. 4. 80 The lower or inwardly-projecting portion of the front face of the swell front *d* is beveled, as at *d*⁶, to dovetail or interlock with the lower edge *b*⁵ of the countersunk portion *b*⁴ of the bin-front *b*².

85 From the upper rim or edge of the swell front *d* projects a screw or similar fastening *d*⁷, arranged to traverse the front face *b*² of the bin *b* and to be engaged by a thumb-nut *d*⁸ or similar locking means arranged to be 90 operated from the interior of the bin proper.

While this fastening and locking means is preferable in tilting or sliding bins where the interior of the bin is readily accessible, yet in stationary bins it may be desirable to reverse 95 this arrangement by making the screw or fastening *d*⁷ project from the bin-front *b*², traverse the display-front *d*, and be engaged by a locking means *d*⁸ outside or in front of said display-front *d*.

100 The false back *d*³ rests on its lower edge upon a block *e*, fitted into the interior of the

display-front, so that the back d^3 will be supported adjacent to the glazed portion d^2 in substantial parallelism therewith. The false back d^3 may be moved on this block e toward or away from the glazed portion d^2 to decrease or increase the display-space and when set in proper proportion is locked by permitting the bolts d^3 to engage the proper slots d^5 in the interior of the swell front.

10. The advantages of our present invention are manifold. Thus, for instance, the swell or display front d may be quickly and easily removed from or secured to the bin-front without disturbing the contents of either the bin or of the display-front, or, if desired, the display-front may be removed and its false back quickly removed to change the contents of the display-front. When once in position upon the bin the contents of the display-front 15 are protected from dust, dirt, accidental disarrangement, and deterioration, being, as heretofore described, completely isolated from the bin proper and from the external atmosphere. If the bins b are to be used without a display-20 front d , it is an easy matter to remove and store said display-front d without disturbing its contents, so that when again required the display-front d may again be secured to the bin. The adjustability of the false back d^4 25 permits of the economical use of materials for display according either to the bulk or value of said materials.

Having thus described the nature and object of our invention, what we claim, and desire to secure by Letters Patent, is—

- 35 1. A bin having a front wall and a display-front removably secured to said wall.
2. A bin having a countersunk front wall and a display-front interlocking in the front 40 wall and detachably secured thereto.
3. A bin having a front wall provided with a central countersunk portion and a display-front having its rear face interlocking with and detachably secured in said countersunk 45 portion of the front wall.
4. A bin having its front wall provided with a countersunk portion, the lower edge of which is inwardly beveled and a display-front having the lower edge of its rear face com-

plementally beveled to interlock or dovetail 50 with the inwardly-beveled edge of said countersunk portion, in combination with means for removably securing the upper edge of said display-front to said front wall of the bin.

5. A bin having a front wall, a display-front 55 projecting beyond said front wall and detachably secured thereto, and a false back arranged within the display-front adjacent to the front wall of the bin.

6. A bin having a front wall, a display-front 60 detachably secured to said front wall, a ledge arranged in the interior of said display-front, and a removable false back supported upon said ledge in parallel relationship with the face of the display-front.

65 7. A display-front arranged to be removably secured to a bin, said front having a glazed face and a false back, in combination with fastening means on said false back arranged to detachably engage a series of slots 70 in the interior of the display-front to thereby vary the space between said back and the glazed front of the bin.

8. The combination with a bin arranged to oscillate or tilt in its chamber or casing and 75 having a front wall, of a display swell front removably secured to the front wall of said bin.

9. The combination with a bin arranged to oscillate or tilt in its chamber or casing and 80 having a countersunk front wall, of a display-front having a glazed face and a false back to form a space for the reception of the goods to be displayed, said display-front arranged to interlock in the countersunk front wall 85 and to be detachably secured therein, whereby the countersunk front wall of the bin seals the rear face of said display-front, as and for the purposes described.

90 In testimony whereof we have hereunto set our signatures in the presence of two subscribing witnesses.

ALEX. H. MILLER.
FRANK A. ENGLAND.
